CLAIM

I claim the ornamental design for a unicorn LED helmet, as shown and described.

DESCRIPTION

FIG. 1 is a front, left perspective view of a unicorn LED helmet showing my new design.

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The evenly broken lines in the figures represent portions of the unicorn helmet that form no part of the claimed design. The unevenly broken lines represent the boundary of the claim and form no part thereof.
